UNITED STATES PATENT OFFICE.

WILLIAM MARRETT, OF TOLEDO, OHIO, ASSIGNOR TO THE LIBBEY GLASS COMPANY, OF TOLEDO, OHIO, A CORPORATION OF OHIO.

DESIGN FOR A CUT-GLASS VESSEL.

SPECIFICATION forming part of Design No. 36,278, dated April 7, 1903.

Application filed February 10, 1903. Serial No. 142,813. Term of patent 7 years.

To all whom it may concern:

Be it known that I, WILLIAM MARRETT, a citizen of the United States, residing at Toledo, in the county of Lucas and State of Ohio, have invented and produced a new, original, and ornamental Design for a Cut-Glass Vessel, of which the following is a specification, reference being had therein to the accompanying drawings, in which—

10 Figure 1 is a perspective view of the inverted vessel; and Fig. 2 is a section on line xx , Fig. 1.

The design is applicable to various vessels of cut-glass ware. In the center of the bottom is a rosette A, surrounded by a star-shaped ornament B. From the inner angles a of the star pairs of radial cuttings C extend to the periphery. Intermediate these pairs of cuttings are festoons formed by oppositely-inclined cuttings D, having an angular intersection b . These cuttings are of angular cross-section, with their inner edges c curved inwardly in opposition to the outer curve of

the cut surface. Thus the outer edges of the cuttings D form oppositely-arranged curves 25 or arcs d and e . The space intermediate the members of each pair of cuttings C is ornamented by cross-cuttings f , and the spaces between the arcs d and e are ornamented by cross fan-shaped cuttings g . 30

The leading feature of the design consists in a vessel having the radial cuttings, with the space intermediate ornamented by festoons formed by oppositely-inclined cuttings of angular cross-section, with their inner edges 35 curved inward and their outward edges forming opposite arcs.

What I claim as my invention is—

The ornamental design for a cut-glass vessel, substantially as described. 40

In testimony whereof I affix my signature in presence of two witnesses.

WILLIAM MARRETT.
